[57] CLAIM

The ornamental design for a compartmented package of tennis balls, as shown and described.

DESCRIPTION

FIG. 1 is a side elevational view of a compartmented package of tennis balls showing my new design; FIG. 2 is a view similar to FIG. 1 but with the bottom, compartment closure in an open position; FIG. 3 is a bottom plan view of FIG. 1 on an enlarged scale;

FIG. 4 is a bottom plan view of FIG. 2 on an enlarged scale; and

FIG. 5 is a top perspective view of FIG. 2 on a scale larger than that of FIG. 2 but smaller than that of FIG. 4.
